BROKEN RAILWAY WHEEL FLANGE DETECTORS

Chalmers W. Gilbert, Penn Township, Allegheny County, Pa., assignor to Westinghouse Air Brake Company, Wilmerding, Pa., a corporation of Pennsylvania
Filed May 13, 1957, Ser. No. 658,694
6 Claims. (Cl. 246—169)

My invention relates to broken railway wheel flange detectors, and particularly to an arrangement whereby the detection of broken flanges is based on the "closed circuit" principle rather than the "open circuit" principle.

Heretofore the operation of broken railway wheel flange detectors has been based on the principle of closing an electrical circuit for indication purposes, when a wheel with a broken flange is in a broken flange detector section provided along a length of railway rail. This is the so-called "open circuit" principle. My invention covers a method based on the so-called "closed circuit" principle wherein the presence of a wheel with a broken flange in a broken flange detector section provided along a length of running rail will cause deenergization of a normally energized indication circuit.

The advantages of signaling systems based on the "closed circuit" principle has long been recognized in the art of railway signaling. In any system using a normally open circuit scheme the failure of any of the associated apparatus, such as a broken wire, a low potential battery, corroded contacts, etc., will cause the system not to function and fail to indicate the proper intelligence to the system. Failures, such as stated above, in systems using a normally closed circuit scheme will cause indication to be given and the failure of the apparatus will be recognized at a much earlier time. In other words, in open circuit systems, a broken flange detector system could be inoperative due to apparatus defects and the failure may not be discovered for a considerable time, the inoperation of the system being considered as the absence of broken wheel flanges. In the second or closed circuit system apparatus defects would cause an indication to be given and the continuance of the indication would serve to indicate defective detector apparatus rather than broken wheel flanges, and the failure of the system will be more readily recognized.

Another advantage of my detector arrangement is that there need be no electrical contact between the wheels of the railway cars or rolling stock and the apparatus of my system. This advantage is readily recognizable, as little dependance can be placed on an electrical circuit to be momentarily closed between a contact point and a railway car wheel, the latter being perhaps rusty, coated with a film of oil or grease or otherwise dirty.

A further advantage of my invention is that the electrical contacts of my apparatus being normally closed there is less opportunity for corrosion to form on these contacts and prevent the completion of the electrical circuits.

Accordingly, one object of my invention is to provide a broken wheel flange detector system based on the closed circuit principle. This is accomplished by the use of a series electrical circuit through normally closed contacts on a plurality of flange detectors located within a section of railway track; and so arranged that the presence of a wheel with a broken flange in said track section will open the series electrical circuit to actuate certain indicating apparatus.

Other objects, advantages, and characteristic features of my invention will become apparent as the description proceeds.

I shall describe two forms of apparatus embodying my

2

invention, and shall then point out the novel features thereof in claims.

In the accompanying drawings:

FIG. 1 is a plan view of a section of railway track showing a length of one of the rails equipped with a series of my broken wheel flange detector devices.

FIG. 2 is an enlarged sectional view of the track rail taken on the line II—II of FIG. 1 showing the presence of an undamaged railway car wheel in the detector section of rail of FIG. 1 and the arrangement of my broken flange detection apparatus.

FIG. 3 is an enlarged sectional view similar to FIG. 2 showing a modified form of my broken wheel flange detection apparatus.

Similar reference characters refer to similar parts in each of the views.

Referring first to FIG. 1, the reference characters 1 and 2 designate the rails of a section of railway track. Reference characters 4 through 28 designate individual broken wheel flange detectors mounted on the inside of the rail 1 as closely to each other as possible without any interference of operation between the individual detectors. For convenience I have shown only twenty-five such detectors but it should be understood that the series of detectors should be of a sufficient number to extend for a distance along rail 1 equal to the circumference of the largest wheel of the rolling stock to pass over the track section and whose wheels it is desired to check.

Along the other running rail, directly opposite the series 30 of detectors, would be mounted a guard rail to assure proper transverse location of the wheels with respect to the flange detectors. The guard rail is designated by reference character 3.

It will be understood that another group of detectors 35 would be installed along rail 2 for detection of broken flanges on wheels running on that rail but cannot be directly opposite the first group due to the necessity of the guard rail. This second group of detectors is not shown in the drawings as it would be a completely independent installation.

Each individual broken wheel flange detector 4 through 28 is connected to the next one in a series electrical circuit so that the entire group of detectors form a continuous series circuit. This arrangement will be further clarified as my description progresses.

The reference character R designates a two-position relay which may be of any type desired. Reference PB designates a spring return push button circuit controller which also may be of any desired type and which is 50 equipped with a normally open contact c. Reference characters GKE and RKE designate green and red indication lamps respectively.

Energy for the operation of the apparatus is furnished by a suitable source of control current, this power source 55 being preferably a battery of proper voltage and capacity but for the sake of simplicity this power source is not shown in the drawings, its positive and negative terminals being identified by conventional reference characters B and N, respectively.

Referring now to FIG. 2, I have here shown the detail construction of the flange detector 4 illustrated in FIG. 1. As here illustrated, the reference characters 50 and 51 designate two electrically conductive contact springs mounted one above the other as shown and which are 60 electrically insulated at one end from electrical contact with each other by a piece of insulating material designated by reference character 52. The lower contact spring 51 is also electrically insulated from its mounting M by a piece of insulating material 53. The method of mounting the individual detectors is not shown as it does 65 not constitute part of my invention and any convenient method of supporting the detectors can be used.

On the top of the rail end of upper contact spring 50 is mounted a pad 54 upon which it is intended that the railway wheel flanges should ride to depress the spring. This pad is made of some form of electrically insulating material to prevent electrical contact between the wheel flanges and the contact spring.

The rail end of lower contact spring 51 extends slightly beyond the rail end of upper contact spring 50 and curves abruptly in an upward direction so as to produce a finger or feeler section F. This finger extends at such an angle as to extend behind the railway wheel flanges and come as close as possible to the railway wheel rims without actually making physical contact therewith.

On the lower part of the rail end of upper contact spring 50 and the upper part of the rail end of lower contact spring 51 are mounted contact points 55 and 56 respectively. These contact points are attached to the individual contact springs in such a manner as to ensure a reliable electrical connection between the springs and points and are mounted directly one above the other so that electrical contact with each other is provided by the inherent resiliency of the contact springs. To the mounting end of the contact springs 50 and 51 is shown connected wires W1 and W2 respectively. These wires are connected to the contact springs in such a manner as to ensure a reliable electrical connection.

It is apparent that due to the initial adjustment of the contact springs 50 and 51, contact points 55 and 56 are closed when there is no railway car wheel on the rail adjacent the individual detector. A closed electrical circuit can, therefore, be made from wire W1 through contact spring 50, contact point 55, contact point 56, contact spring 51 to wire W2. It is also apparent that the presence of a railway car wheel with an unbroken flange would cause a depression of contact spring 50 by the flange riding on the insulating pad 54, the contact points 55 and 56 would be kept in a closed position and the electrical circuits described would be maintained. However, the presence of a wheel with a piece of flange broken out at the point where the wheel passes over the detector would fail to depress contact spring 50 but the upturned finger F of contact spring 51 would contact the rim of the wheel and be depressed, and the contact points 55 and 56 would therefore be separated or open to break the described electrical circuit.

Referring now to FIG. 3, in the modified form of detector here illustrated, references 50, 51, 52, 53, W1, W2, F and M designate identical parts referred to in FIG. 2 the only difference being in the location where the wires W1 and W2 are connected. The same reference designations are used for these wires in both FIGS. 2 and 3 so that either detailed modification of individual detector apparatus can readily be applied to the drawing of FIG. 1.

Reference character 58 in FIG. 3 corresponds to reference character 54 of FIG. 2 but in FIG. 3 a hardened steel block or pad is preferably used for reference 58 to better withstand the abrasion caused by physical contact with the wheel flanges of the railway rolling stock. On the lower side of contact spring 50 in FIG. 3 is attached a stud 59 which makes physical contact with a plunger or actuator P of a switch S. The switch S is a short stroke switch (commercially known as a microswitch) of a type which has a normally open contact, that is, its plunger P must be depressed against internal spring pressure to close the contact of the switch. The contact springs 50 and 51 are so stressed that stud 59 is forced against the plunger P with sufficient pressure to overcome the pressure of the internal spring of the switch S so that its contact will be held normally closed to complete an electrical circuit. The wires W1 and W2 are connected to each side of the contact of the switch S and a closed electrical circuit can be made from wire W1 through the closed contact of switch S to wire W2.

It can be seen that the apparatus of FIG. 3 operates similarly to that of FIG. 2, that is, the absence of a wheel

or the presence of a wheel with an unbroken flange would keep plunger P depressed and maintain an electrical circuit through the contact of switch S, from wire W1 to wire W2. However, the presence of a wheel with a broken flange would cause depression of contact spring 51 but not contact spring 50, the plunger P would be forced upward by the internal spring pressure of the switch S and the contact of the switch would open to break the electrical circuit from wire W1 to wire W2.

10 Referring again to FIG. 1, under normal conditions, that is, with no railway car wheel in the detector track section or with a car wheel with an unbroken flange in the detector section an electrical circuit is completed to retain indication relay R energized over a circuit which 15 may be traced from terminal B of the source through wire W1 connected to individual detector reference 4 and, assuming that detectors as shown in FIG. 2 are being used, contactor spring 50 of detector 4, contact point 55, contact point 56, contact spring 51, wire W2 of detector 20 4, wire W1 of detector 5, contactor spring 50 of detector 5, contact point 55, contact point 56, contact spring 51, wire W2 of detector 5, wire W1 of detector 6, contact spring 50 of detector 6, contact point 55, contact point 56, contact spring 51, wire W2 of detector 6, and so 25 forth through the entire series of detectors to wire W2 of the last of the series (here shown as reference 28), wire 85, front contact a of relay R, wire 86, wire 87, winding of relay R, and wire 88 to terminal N of the source. It is thus apparent that relay R is normally held 30 in the energized position over a stick circuit including its own front contact a.

With relay R in the energized position, a circuit is completed to illuminate the green indication lamp GKE. This circuit may be traced from terminal B of the source 35 through wire 99, the front point of contact b of relay R, wire 91, lamp GKE, and wire 93 to terminal N of the source. Lamp GKE being illuminated serves to indicate the presence of no wheels with broken flanges in the detector section of rail.

40 Assuming that a wheel with a piece broken from its flange enters the detector section, the circuit to relay R described above will be opened when the location of the broken flange reaches detection position in the series of detectors, that is, when this point on the wheel is riding on the rail. As heretofore described the rim of the wheel 45 as shown in FIG. 2 will cause depression of contact spring 51 by physical contact with upturned finger F but no depression of contact spring 50 will be caused as the piece of flange that should come into contact with pad 54 is missing from the wheel. The depression of contact spring 51 will separate contact point 56 from contact point 55 and open the energizing circuit to relay R.

50 Deenergization of relay R will cause the front point of contact b of that relay to open extinguishing the green 55 indication lamp GKE and cause the back point of contact b to close to complete a circuit to the red indication lamp RKE to give a broken flange indication. This latter circuit may be traced from terminal B of the source through wire 90, the back point of contact b of relay R, wire 92, red indication lamp RKE, and wire 94 to terminal B of the source.

Deenergization of relay R also opens the stick circuit 60 through its own front contact a and relay R will remain in the deenergized position after the broken flange is no longer in the detecting position and until push button controller PB is operated to reenergize relay R. This type of operation will insure that the railway operator or the responsible personnel will have knowledge of the wheel with a broken flange. The circuit for reenergization of relay R may be traced from terminal B of the source through wire W1, the entire series of detectors 4 through 28, wire W2, wire 89, back contact c of push button controller PB, wire 87 and to winding of relay R to terminal N of the source. The depression of button PB will 65 reenergize relay R to thereby reestablish the stick circuit 70 75

over its own contact *a*, and thus extinguish the indication lamp RKE and illuminate lamp GKE. The circuits are then again in the normal position.

The circuits of FIG. 1 using the individual detector apparatus as shown in FIG. 3 would, of course operate in the identical manner as that described using detector apparatus of FIG. 2, except the presence of a wheel with a broken flange in the detector section would cause the energizing circuit for relay R to be opened by the contact of the microswitch S.

From this description it is apparent that with apparatus of my invention arranged as shown in FIG. 1 of the drawings a system, based on the "closed circuit" principle, for detection of broken flanges on the wheels of railway rolling stock is provided.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. A mechanically actuated railway car wheel broken flange detector comprising a first contact spring located adjacent a rail within a section of railway track in the path of a railway car wheel traversing the rail so as to be depressed by the flange of the railway car wheel; a second contact spring mounted below and extending beyond, up, and behind said first contact spring and arranged so as at times to be depressed by said first contact spring and at times to be depressed by the rim of a railway car wheel; and a normally closed electrical contact maintained in said closed position when said second contact spring is depressed by said first contact spring, and permitted to open when said second contact spring only is depressed by the rim of a railway car wheel.

2. A mechanically actuated railway car wheel broken flange detector comprising a first contact spring and a second contact spring, said first contact spring being located adjacent a rail within a section of railway track in the path of a railway car wheel traversing the rail so as to be depressed by the railway car wheel flange and said second contact spring being so located in relationship to said first contact spring as to be depressed at times by said first contact spring and at times by a railway car wheel rim; and a normally closed electrical contact maintained closed when said second contact spring is depressed by said first contact spring and open when said second contact spring only is depressed by a railway car wheel rim.

3. A mechanically actuated broken railway wheel flange detector comprising first and second contact springs; said contact springs being so located adjacent a rail within a section of railway track in the path of a railway car wheel traversing the rail that a wheel having a normal flange adjacent said detector depresses said first contact spring and said first contact spring depresses said second contact spring, and a wheel with a piece broken from its flange directly opposite said detector depresses only said second contact spring; and a normally closed electrical contact opened when said second contact spring only is depressed.

4. Apparatus for the detection of broken flanges of wheels having rims traversing a rail, said apparatus comprising a first means for detecting a flange of a wheel, a

second means for detecting the rim of said wheel simultaneously, a third means controlled by said flange detecting means for controlling said rim detecting means, and indication circuit means controlled by said third means for controlling said indication circuit means when a wheel passes having a broken flange.

5. A detector for a broken flange of a wheel having a rim which rests on a rail and a flange, said detector comprising a mounting of insulating material, a pair of spaced electrically conducting contact springs fastened at one end to said mounting, a pair of contacts fixed to the spaced contact springs at their ends opposite the mounting and biased in a normally closed position bridging the spacing between the springs, an indication circuit connected in series with said contacts and springs, a pad fixed on the end of one of the springs in the path of travel of the wheel flange and depressed thereby, the depression of the pad forcing both springs in one direction as a unit and maintaining the contacts closed, and a finger on the other spring extending to a point adjacent the rim of the wheel and biased out of contact with the rim by the pressure of a flange on the pad of the spring, the finger being located in the path of travel of the rim of a wheel and depressed thereby to open the contacts in the absence of a flange simultaneously in contact with the pad.

6. A detector for a broken flange of a wheel having a rim which rests on a rail and a flange, said detector comprising a mounting, a pair of spaced springs fastened at one end to the mounting, an electrical switch having a mechanical bias to an open-circuit condition and mounted on one of said springs, said switch including an actuator, a stud mounted on the other of said springs in the space between the springs to press against the actuator of the switch to maintain it in a closed-circuit condition against said mechanical bias, an indication circuit connected to said switch, a pad fixed on the end of said other spring in the path of travel of the wheel flange and depressed thereby, and a finger on said one spring extending to a point adjacent the rim of the wheel and biased out of contact with the rim by the pressure of the flange on the pad of said other spring through the stud and switch actuator, the presence of a rim without a flange depressing the finger and separating the contact between the stud and the switch actuator to open the switch.
